UNITED STATES PATENT OFFICE

FRASIER SMITH, OF WHEELING, WEST VIRGINIA, ASSIGNOR TO HAZEL-ATLAS GLASS COMPANY, OF WHEELING, WEST VIRGINIA, A CORPORATION OF WEST VIRGINIA

DESIGN FOR A BOTTLE

Application filed May 3, 1933. Serial No. 47,985. Term of patent 7 years.

To all whom it may concern:

Be it known that I, FRASIER SMITH, a citizen of the United States, residing at Wheeling, in the county of Ohio and State of West Virginia, have invented a new, original, and ornamental Design for a Bottle, of which the following is a specification, reference being had to the accompanying drawing, forming part thereof.

The figure is a perspective view of a bottle showing my new design.

I claim:

The ornamental design for a bottle, as shown.

FRASIER SMITH.
